JULIEN PIETERS, OF PARIS, FRANCE.

CHARGING APPARATUS FOR CONTINUOUS VERTICAL OVENS, MORE PARTICULARLY COKE AND GAS OVENS.

1,308,641.

Specification of Letters Patent.

Patented July 1, 1919.

Application filed January 23, 1918. Serial No. 213,368.

To all whom it may concern:

Be it known that I, JULIEN PIETERS, engineer, a subject of the King of Belgium, and a resident of 10 Rue de Rome, Paris, France, have invented new and useful Improvements in Charging Apparatus for Continuous Vertical Ovens, More Particularly Coke and Gas Ovens, of which the following is a specification.

10 This invention relates to a charging apparatus of continuous coke or gas ovens, and, more generally, of any vertical distilling apparatus, intended to insure distribution of coal or other material to be distilled in one or more ovens arranged in series or in a battery, regular progress or advance of the said material in each of the ovens, and to maintain the same closed in an air tight manner by the sole action of the mass of coal or 20 other material to be distilled.

In existing vertical ovens already used for the manufacture of the lighting gas, the advance of the coal in the distilling apparatus is produced exclusively by the simple 25 action of gravity. This has however several serious drawbacks.

(a) Owing to the adhesion of the coal to the apparatus at the beginning of its descent, the latter is not uniform; arches are 30 produced in the coal which are even liable to stop the descent altogether; and additional labor is required to remedy it.

(b) The coke subsequently produced by distillation of the coal, is also liable in certain cases to adhere very strongly to the wall of the oven, to such an extent that the weight of the whole mass of coke and coal above the level of stoppage is no longer sufficient to detach the adhering portion and 40 to force the block of coke and coal to descend. This is a fairly serious drawback, as the removal requires then a temporary stopping of the oven so as to enable this cause of disturbance to be removed.

45 In the event of coke being manufactured in a continuous vertical oven, these two drawbacks would make it impossible to obtain a suitable result from the metallurgical point of view.

(c) Finally, this irregularity in the simple descent under the action of gravity, and the empty places necessarily existing then in the mass, make it imperative to use a special device for maintaining a sufficiently tight 55 joint at the upper part of the oven, and for

preventing at the same time either the escape of the gases of distillation, or the admission of air through the same inlet as that for the coal, owing to a pressure or to a depression existing in the oven, according to 60 the working of the gas extractor in the works for recovering the by-products.

These drawbacks can be done away by the apparatus according to the invention, by making the charging of coal and its advance 65 in the oven absolutely automatic, uniform and reliable, and insuring a perfectly tight joint, given the conditions of pressure that can exist in normal working.

This new device chiefly comprises an apparatus used for distributing the coal in a thoroughly uniform manner over the whole extent of the oven, or of all the ovens arranged in a battery, then for producing a certain pressure at any desired moment, 70 when it is desired, or at regular intervals of time, according to the regulation adopted. This uniform distribution of coal (or of fine particles of any material to be distilled) throughout the whole extent of the oven, and the subsequent pressure, prevent any empty spaces from being formed, and by bringing all the particles very close together, produce a very compact mass through which, owing to its comparatively great height, no gases 75 can pass either in one or in the other direction, even at higher pressures than those that could normally exist in coke ovens.

The considerable pressure exercised by the charging apparatus at the top of the 80 furnace, added to the simple action of gravity on the whole mass of coal and coke (or other material to be distilled), is sufficient to cause the said mass to advance in an absolutely uniform manner, even if important 85 adhesions were produced at the inner walls of the oven, along which the coal and the coke have to slide. Owing to this pressure and to the regular advance of the coal throughout the whole of its mass, the coke 90 obtained will also have a regular, constant and properly homogeneous texture, its hardness will be increased, and consequently its metallurgical value will be greater. It will be even possible to obtain good metallurgical 95 coke from comparatively thin and very slightly caking coal which, in ordinary ovens, would not give any product that could be advantageously used in metallurgy.

The accompanying drawing shows, by 110

way of example, in vertical axial section, a construction according to the invention, applied to a battery of ovens.

An endless chain *a* to which are secured 5 scrapers *b* arranged at regular intervals, is supported by a girder *c* extending throughout the whole length of the battery of ovens to be served. This girder rests at the two 10 ends on the spindle of drums *d* and *e* used to drive the chain. At regular intervals to the chain are also secured, so as entirely to participate in its movement, one or two rollers *f*. The latter are intended to exercise, simply by their passage, a slight pressure, 15 sure on the particles of coal, the said pressure being sufficient to insure a tight joint.

The bearings *d*¹ and *e*¹, supporting the spindles of the two drums *d* and *e* of the chain *a*, are carried by plates or disks *g* 20 which can be raised by hydraulic pressure pistons *h*. In normal time, the whole weight of the movable part—drums, girder supporting the chain and a portion of the weight of the latter—is supported solely by the hydraulic pistons *h*. If the pressure on the latter is reduced, a portion of or even the whole of this weight will rest on the roller or rollers *f*. The latter, in passing above the various ovens, will therefore exercise on 25 the coal, piled up to a great height in the passages *i* arranged in the upper portion of the ovens (not shown) a pressure which can be very considerable, owing to the very high total weight of the movable part. A handle *h*¹ operated by the attendant intrusted with the supervision of the charging apparatus, and regulating the admission or discharge of water under pressure coming from an accumulator under the pistons *h*, makes it possible to graduate the 30 pressure to be exercised on the mass of coal. The admission of coal or material to be distilled is at *j*. In order to insure a great elasticity in the regulation of the admission of coal, the chain with scrapers, as well as the whole of the girder *c*, can be raised in the interior of a reservoir *k* to a certain height, so as to allow coal to accumulate, this acting as a flywheel regulator on the 35 supply of coal to the various ovens.

It goes without saying that various constructional modifications can be made in

the apparatus hereinbefore described, provided that it retains the essential characteristic features: uniform distribution of the charge, and pressure exercised at the upper part of the oven or ovens, for the purpose of insuring a sufficiently tight joint of the mass, and of forcing the latter to descend in the measure as the coke or other material obtained by distillation is removed at the bottom end of the vertical oven.

Claims:

1. In a coking oven, an oven chamber open at the top, a charging hopper open to said top, and means in said hopper for feeding the charge to said oven and compacting the upper portion of a charge therein to form a seal against the escape of gases from the top of the oven during the coking operation. 70

2. In a coking oven, an oven chamber open at the top, a charging hopper open to said top, a traveling feeder working in said hopper to charge the oven through the open upper end thereof and pressors carried by said feeder for compacting the charge in the top of the oven to form a seal against the escape of gases at the top of the oven during the coking operation. 75

3. In a coking oven, an oven chamber open at the top, a charging hopper communicating therewith, and means vertically reciprocal in said hopper to compress the upper portion of the charge in the oven and thereby form a seal against the escape of gases from the open top of the oven during the coking operation. 80

4. In a coking oven, an oven chamber open at the top, a charging hopper communicating therewith, a traveling feeder working in the hopper and serving to feed a charge to the oven chamber through the open end thereof, and a vertically reciprocal frame carrying said feeder and coöperating therewith to compact the upper portion of the charge in the oven, for the purpose described. 90

In testimony whereof I have signed my name to this specification.

JULIEN PIETERS.
